DESIGN FOR A SHOE OR SIMILAR ARTICLE

Wallace Bradley Mackey, Upper Montclair, N. J.

Application April 23, 1935, Serial No. 56,517

Term of patent 7 years

To all whom it may concern:

Be it known that I, Wallace Bradley Mackey, a citizen of the United States, residing at 75 Oakwood Avenue, Upper Montclair, in the county of Essex and State of New Jersey, have invented a new, original, and ornamental Design for a Shoe or Similar Article, of which the following is a specification, reference being had to the accompanying drawing, forming part thereof.

Fig. 1 is a side elevation of a shoe, showing my new design;

Fig. 2 is a front elevation of a shoe, but on a slightly reduced scale to that shown in Fig. 1; and
Fig. 3 is a fragmentary rear elevation of the same.

I claim:

The ornamental design for a shoe or similar article, as shown.

WALLACE BRADLEY MACKEY.
